UNITED STATES PATENT OFFICE.

JOHN O. CARREY, OF ST. LOUIS, MISSOURI.

BRUSH.

Application filed November 10, 1921. Serial No. 514,224.

To all whom it may concern:

Be it known that I, JOHN O. CARREY, a citizen of the United States, residing at St. Louis, Missouri, have invented a certain 5 new and useful Improvement in Brushes, of which the following is a full, clear, and exact description, such as will enable others skilled in the art to which it appertains to make and use the same, reference being had 10 to the accompanying drawings, forming part of this application.

This invention relates to a new and useful improvement in brushes, and the objects of the invention are to provide a brush having 15 bristles which can be readily compacted so as to facilitate their insertion into the recesses and cavities of machine parts desired to be cleaned, such as spark plugs.

Other objects of the invention are to provide 20 manually operable means for compacting the ends of the bristles of the brush, said means being operable to release said bristles so that the latter can assume their operative positions.

With these and other objects in view my 25 invention consists in certain novel features of construction and arrangements of parts hereinafter more fully described and claimed and illustrated in the accompanying 30 drawings in which,—

Figure 1 is a perspective view of the brush.

Figure 2 is a side elevation thereof.

Figure 3 is a similar view showing the 35 bristles compacted and ready to be inserted in position.

Figure 4 is a view looking against the underside of the brush.

Figure 5 shows a modified form of brush. 40 Figure 6 is a plan view of the lower end of the modified form of brush.

Referring by numerals to the accompanying drawings, 10 designates the back of the brush in which are seated in the usual manner tufts of bristles or wire members 11. Bristles or wire members 12 are seated in one end of said brush and are spaced a suitable distance from the bristles 11. Encircling said bristles 12 is the lower loop end 45 13 of wire 14 which extends upwardly through an aperture 15 formed in the back or handle 10. The upper end 16 of this wire is bent at right angles thereto and projects longitudinally beyond the end of said 50 brush. This end is preferably flattened or stamped to assume the desired thickness,

whereupon it can be used in gauging the proper distance between the ends of the spark plug electrodes. The outwardly projecting end 16 forms a handle by means of 60 which wire 14 may be properly manipulated and at the same time prevents withdrawal of said wire from its seat in the back 10. The lower end 13 is also flattened, only in this case, the flat walls are disposed vertically in order to engage bristles 12. The loop formed by this end is shaped so as to conform to the curvature of the wall of the spark plug in order to properly assemble the 65 ends of the bristles 12 and enable the easy 70 insertion thereof in the lower end of the spark plug.

In using the brush for cleaning a foul 75 spark plug, the operator presses on handle 16, thereby depressing the wire 14 and causing its lower loop end 13 to compact or press together the lower ends of bristles 12. The compacted ends of bristles 12 are positioned in the spark plug and the brush is 80 pressed against the same so that bristles 12 85 are moved into the spark plug cavity, while wire 14, by virtue of the fact that its loop end 13 bears against the edge of the spark plug, is moved outwardly through aperture 15 to its extreme outer position. The plug or brush, as the case may be, is then manipulated so as to cause bristles 12 to move over the inner walls of the plug thereby 90 loosening and removing carbon therefrom.

In the modified form shown in Figures 5 90 and 6, brush 17 is provided with an upwardly extending rod 18, which is slidably received in tubular member 19. The lower end 20 of this tubular member is so shaped 95 as to give the bristles 21 of brush 17 the required form. By pressing on button 22 fixed to the upper end of rod 18, brush 17 is caused to move downwardly, and bristles 21 move outwardly from the lower end 20 of rod 18 into operative position. Bristles 11 100 are used for cleaning purposes in the usual manner. By using wire 14, bristles 12 can be easily and quickly confined within a limited space, and by properly shaping the looped end 13, the ends of the bristles can 105 be given any desired shape in order to facilitate their positioning in the cavity desired to be cleaned.

When member 14 is moved upwardly, loop 15 will have a tendency to force the ends 110 of bristles 12 outwardly into operative position.

A brush constructed according to my invention is simple in construction, inexpensive to manufacture, and can be used as an ordinary brush or for cleaning the inner walls of spark plugs or gauging the distance between the ends of electrodes.

Obviously, various minor changes in the form and construction of my improved brush can be made and substituted for those herein shown without departing from the spirit of my invention:

What I claim is:

1. In combination with a brush back having bristles, of a member movably mounted through the handle of said brush, and having a semi-circular band portion encircling and compressing said bristles the area of said band being less than the base of said bristles whereby when said member is moved to position said band portion adjacent to the base of said bristles the latter are distorted so as to cause the free ends thereof to assume expanded positions.

2. In combination with a brush back having bristles, of a rigid member movably arranged through said brush back in parallelism with said bristles and provided with a bridle encircling and compressing said bristles the area of said bridle being less than

the base of said bristles whereby when said member is moved in one direction the bridle thereof compresses and shapes the free ends of said bristles and when said member is moved in the opposite direction said bridle compresses the base portions of said bristles thereby distorting said bristles and expanding the free ends thereof.

3. In combination with a spark plug brush back having bristles, a member slidably mounted through said brush back adjacent to said bristles, said member being provided at its lower end with a semi-circular loop portion for encircling and shaping said bristles and at its upper end with a lateral extension adapted to be used in gauging the spark gap of the plug electrodes, the area of said loop being less than the base of said bristles whereby when said loop is moved adjacent the free ends of said bristles the latter are compressed and shaped to facilitate their insertion in the spark plug and when said loop is moved toward the base of the bristles the latter are stressed causing the free ends thereof to expand.

In testimony whereof I hereunto affix my signature this 2nd day of November, 1921.

JOHN O. CARREY.
